UNITED STATES PATENT OFFICE

93,634

DESIGN FOR A JUG

Jacob P. Rosenbaum, Denver, Colo.

Application August 6, 1934, Serial No. 52,849

Term of patent 7 years

To all whom it may concern:

Be it known that I, JACOB P. ROSENBAUM, a citizen of the United States of America, residing at Denver, in the county of Denver, and State of Colorado, have invented a new, original, and ornamental Design for a Jug, of which the following is a specification, reference being had to the accompanying drawing, forming part hereof.

Fig. 1 is a front elevation illustrating the design of the jug.

Fig. 2 is a top view thereof.

Fig. 3 is a rear elevation thereof.

I claim:

The ornamental design for a jug as shown.

JACOB P. ROSENBAUM.
